Patented Feb. 10, 1970

216,549

GOLF CLUB GRIP

Victor E. Dworak, Huntington Beach, Calif., assignor to
W. J. Voit Rubber Corp., a corporation of California

Filed Dec. 10, 1968, Ser. No. 14,867

Term of patent 14 years

Int. Cl. D21—03

U.S. Cl. D34—5

FIG. 1

FIG. 2

FIG. 3

FIG. 4

FIG. 5

FIG. 1 is a side elevation view of a golf club grip embodying the design;

FIG. 2 is a top plan view of the golf club grip;

FIG. 3 is an elevation view of the other side of the grip;

FIG. 4 is a right hand end view; and

FIG. 5 is a left hand end view.

I claim:

The ornamental design for a golf club grip, substantially as shown.
